(57) **CLAIM**

The ornamental design for a fumigation facilitating and bug-resistant covering, as shown and described.

DESCRIPTION

FIG. 1 is a front perspective view of a fumigation facilitating and bug-resistant covering, showing my design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a magnified view of a mesh weave of the covering;

FIG. 8 is another front perspective view thereof;

FIG. 9 is a front perspective view of a second embodiment thereof;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a front perspective view of a third embodiment thereof;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is an exploded view thereof.

The surface shading on the top surface indicates a solid surface and the surface detail of the sidewalls denotes a mesh material as shown in the expanded view of FIG. 7. The broken line showing of environmental structure forms no part of the claimed design.
